DESIGN FOR A GRAVE MARKER

Charles T. Spear, St. Paul, Minn.

Application July 2, 1932, Serial No. 44,241

Term of patent 14 years

To all whom it may concern:

Be it known that I, CHARLES T. SPEAR, a citizen of the United States, residing at St. Paul, county of Ramsey, and State of Minnesota, have invented a new, original, and ornamental Design for a Grave Marker, of which the following is a specification, reference being had to the accompanying drawing forming part thereof.

Figure 1 is a plan view of a grave marker showing my new design.

Fig. 2 is a side elevation, partly in section on line 2—2 of Fig. 1

I claim:

The ornamental design for a grave marker substantially as shown.

CHARLES T. SPEAR.
